MATTRESS

Max Koenigsberg, Highland Park, Ill., assignor to The Englander Company, Inc., Chicago, Ill., a corporation of Delaware

Filed Oct. 23, 1958, Ser. No. 53,109

Term of patent 14 years

(Cl. D5—2)

Fig. 1 is a perspective view of a mattress embodying my new design;

Fig. 2 is an enlarged detail view of a portion of the mattress border structure; and

Fig. 3 is a sectional view on the line 3—3 of Fig. 2. A dominant feature of my design is the appearance produced by the stitching as shown, wherein the adjacent and remote apices of the zig-zag lines of stitching are more widely spaced apart than the intermediate portions thereof.

I claim:

The ornamental design for a mattress, substantially as shown and described.
